INFANT'S GARMENT

Ila Mae Riggs, Montgomery, Ala.

Application April 20, 1948, Serial No. 22,080

5 Claims. (Cl. 128—287)

1

My present invention relates to an infant's garment and has for an object the provision of a garment especially adapted to serve both as an outer garment and as a holder for an absorbent, disposable pad or diaper.

Another object is to provide a garment of the character designated which is secured to the infant's body by cloth tie strings, carried on the upper edge of the front and rear portions of the garment, and embodying side flaps disposed to fold over the tie strings, together with buttonless and pinless fastening means for securing the flaps, whereby when the garment is in place on the body, the cloth tie strings are substantially inaccessible to the infant and concealed from view.

Another object of my invention is to provide a garment of the character described which shall provide maximum coverage for the infant's body, especially at the sides, by providing side flaps foldable around the sides of the body and secured by straps to the front or abdominal portion of the garment.

In the art to which my invention relates, garments heretofore have been provided wherein the front and back portions were secured together after being placed around the body by means of cloth tie strings, snaps, buttons and the like. In all such garments with which I am familiar, the fastening means for the front and back have been left exposed where they are accessible to the infant for untying, unbuttoning, or unsnapping. Neat appearance as well as the utility of such garments have thus been considerably lessened.

It is the prime object of my invention to overcome the above difficulties and to provide an infant's garment of the character designated which shall be simple and inexpensive, neat in appearance, and be so held about the body that the infant cannot remove the same.

A garment embodying the features of my invention is illustrated in the accompanying drawing forming a part of this application in which:

Fig. 1 is a plan view of the garment in unfolded position, as viewed from the inside thereof, and showing a disposable pad or diaper in place;

Fig. 2 is a view similar to Fig. 1 showing the outer surface of the garment;

Fig. 3 is a front elevational view showing the front portion of the garment secured by the tie strings to the back portion thereof, the side flaps for covering the tie strings being in unfolded position; and,

Fig. 4 is a front elevational view of the garment as the same would appear when worn by an infant.

2

Referring now to the drawings for a better understanding of my invention, my improved garment comprises a body 10 preferably made of water repellent cloth and cut generally in plan to the shape of an hour glass. The back portion B of the body is slightly wider than the front portion F thereof as shown clearly in Figs. 1 and 2, and the entire periphery of the body may be bound with bias tape 11 in the customary manner.

10 Slightly below the upper edge of the back portion B, and on the inside thereof, I secure by sewing a length of cloth tape or the like 12. The stitching stops short of the ends of the tape, thereby to provide free ends 13 and 14. On the outer surface of the front corners 16 and 17 of the front portion F I secure by stitching a pair of tie strings 18 and 19.

On the outer surface of the front portion F adjacent the upper edge and centrally of the width thereof, I secure by stitching a cloth strap 21. The stitching stops short of the ends of the strap 21 thereby leaving free ends 22 and 23. On the corners 24 and 26 of the back portion B, on the outside surface thereof, I provide a pair of ring fasteners 27 and 28. The ring fasteners are secured to the corners 24 and 26 by means of straps 29 and 31, passing through the rings and sewed to the corners.

20 On the inner surfaces of the back and front portions B and F, I sew the ends of a pair of straps 32 and 33. The straps 32 and 33 are left unsewed along the central portions thereof, whereby a disposable pad or diaper 34 may have its ends engaged behind the straps, thereby to hold the same place.

30 35 From the foregoing the method of constructing and using my improved garment will be readily understood. As stated, the body 10 preferably is made of a relatively heavy water repellent fabric, cut to hour glass formation in plan view, the front portion F being slightly narrower than the back portion B. The binding is placed around the edges and the straps, tie strings, and ring fasteners are sewed in place. The disposable pad 34 is placed

40 45 behind the straps 32 and 33 simply by inserting the ends of the pad beneath the straps, and the garment is ready for placing about the infant's body. The back and front portions are brought up about the body, and the tie strings 13—18 and 14—19 are tied in a bow knot in the manner shown

50 55 in Fig. 3. This leaves the corners 24 and 26 of the back portion B to be folded around the side of the infant's body and over the resulting bow knots formed by the tie strings. The corners 24 and 26 are now folded around the infant's body, and the ends 22 and 23 of the straps 21 are inserted

through both rings of their respective pair of rings, thence over one of the rings and under the other, thereby making a non-slip connection. Thus positioned, it will be apparent that the corners 24 and 26 completely cover and hide the bow knots formed by the tie strings, thus preventing the infant from untying the same and adding materially to the appearance of the garment. The width of the back portion B may be made more or less greater than the width of the front portion F as desired, depending upon whether or not the garment is to be full or sparingly cut.

Referring again to Fig. 4 of the drawing, I may form the body of the garment of three layers of fabric. The two outer layers 26 and 27 may be formed of relatively soft water absorbent cloth material, while between these two layers I may provide a sheet of water proof material 38, held at its edges by the stitching used to hold the tape 11 around the periphery of the garment. This construction provides a water proof garment while preventing the relatively rough layer 38 from coming in contact with the infant's body.

It is to be noted that the strap 12 is slightly beneath the upper edge of the back portion B and that the points of attachment of the free ends are removed inwardly of the body from the corners 24 and 26. When the free ends 13 and

14 thereof are tied to the strings 18 and 19, the resulting knots are low enough for the corners 24 and 26 to completely cover and hide the same, and folded inwardly far enough to permit the corners 24 and 26 to fold thereover. In practice, I have found that a garment made in accordance with my invention is entirely satisfactory in every way and that the same is neat and pleasing in appearance.

I have also found that no snaps or other fasteners are required to hold the disposable pad 34 in place, the centrally open straps 32 and 33 being entirely satisfactory for that purpose. The absence of fastening means between the pad 34 and the garment makes removal and replacement of the pad much more convenient than in those types of garments wherein such fastening means are employed.

From the foregoing, it will be apparent that I have devised an improved infant's garment which is simple of manufacture, which embodies portions disposed to make inaccessible to the wearer and hide from view the securing means between the front and back portions thereby making it difficult for the infant to release the securing means, and increasing materially the neat appearance of the garment.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are specifically set forth in the appended claims.

What I claim is:

1. In an infant's garment of the character described, a cloth body of hour glass formation in plan, the back portion of the garment being wider than the front portion, fastening means carried on the inner side of the back portion and connected thereto at points removed inwardly of the body from the corners of the back, complementary fastening means carried on the corners at the front of the body, the corners of the back portion being constructed and arranged to overlap the corners of the front portion and overlie said fastening means, and means to secure the rear cor-

ners to the front portion when in overlapped position with respect thereto.

2. In an infant's garment of the character described, a cloth body of hour glass formation in plan, the back portion of the garment being wider than the front portion, tie strings secured to the inside of the back portion at points removed inwardly of the body from the corners of the back portion, tie strings carried on the outside of the corners at the front of the body and adapted to be tied with the strings secured to the back portion, the corners of the back portion being constructed and arranged to overlap the corners of the front portion and overlie said tie strings, ring fasteners carried on the outside of each of the corners of the rear body portion, and a strap secured to the outer side of the front of the body portion and having free ends adapted to engage the ring fasteners carried on the corners of the back portion, thereby to secure the back corners in overlapped relation with respect to the front of the garment.

3. In an infant's garment of the character described, a body of hour glass formation in plan and formed of water repellent cloth, the portion of the body forming the back of the garment being wider than the portion forming the front thereof, the upper corners of the back being disposed to overlap the front corners of the garment, a tie string disposed transversely of the back portion on the inside thereof and slightly below the upper edge of the back, said tie string being sewed to the body along its central portion thereby to leave a pair of free ends, separate tie strings sewed on the outer side of the front corners of the body and disposed to be tied with the free ends of the tie string carried by the back portion, straps on the front and rear portions adapted to receive the ends of a disposable pad, ring fasteners secured to the outer surface of the corners of the rear portion of the garment, and straps on the outer surface of the front of the garment disposed to innerlock with the ring fasteners thereby to hold the rear corners in overlapped relation with respect to the front corners.

4. In an infant's garment of the character described, a body formed of cloth cut to hour glass shape in plan to provide a garment wherein the back portion is wider than the front portion, the corners of the front and back portions being rounded, a cloth strip on the inner surface of the back slightly below the upper edge thereof and having a free end at each side to provide tie strings connected to the back at points inwardly removed from the rounded corners of the back, separate cloth tie strings sewed to the outer surface of each of the rounded corners of the front portion and disposed to be tied to the strings of the back portion, sets of ring fasteners secured to the outer surface of each corner of the back portion, and a cloth strap secured to the outer surface of the front portion adjacent the upper edge thereof and having free ends engageable with the sets of ring fasteners, said corners of the rear portion being disposed to overlap the corners of the front portion and to cover the tie strings when the garment is placed on an infant's body.

5. An infant's garment in accordance with claim 4 in which the body comprises inner and outer layers of water absorbent cloth, and an inner layer of waterproof material.
